DESIGN FOR A STOVE.

Design No. 13,719, dated March 13, 1813.

UNITED STATES PATENT OFFICE.

WILLIAM L. McDOWELL, OF LOWER MERION, PENNSYLVANIA.

DESIGN FOR A STOVE.

SPECIFICATION forming part of Design No. 13,719, dated March 13, 1883.

Application filed January 10, 1883. Term of patent 7 years.

To all whom it may concern:

Be it known that I, WILLIAM L. McDOWELL, a citizen of the United States, residing at Lower Merion, in the county of Montgomery, State of Pennsylvania, have invented and produced a new and original Design for Stoves, of which the following is a specification, reference being had to the accompanying photographic illustration, forming part thereof.

10 My design for stove consists of the cylinder formed in paneled sections, and of other features, as will be hereinafter fully set forth.

15 A represents the dome of the stove; B, the upper section of the cylinder; C, the lower section of the cylinder; D, the plate at the bottom of the cylinder; E, the walls of the ash-pit; F, the ash-pit doors, and G a foot-rest. The section B has a series of doors, which impart a paneled appearance to said section, and

20 the section C is formed of connected panels. The plate D is cut away at the middle of the front, so as to present projecting corners D', and the foot-rest is supported on the pedestals H, which rise from the base of the stove. Each door F is of the form of a half of an ellipse, so

25 that the two doors form a complete elliptical-shaped figure, and on the face of each door is a damper, F'.

I claim—

1. The design for stove, consisting of the upper section, B, of the cylinder, with doors presenting the appearance of panels, substantially as above described and shown.
2. The design for stove, consisting of the cylinder formed of two paneled sections, B C, substantially as above described and shown.
3. The design for stove, consisting of the two-part panel cylinder B C, with the plate D at the bottom of the cylinder, having projecting corners D', substantially as above described and shown.
4. The design for stove, consisting of the two ash-pit doors, forming together an elliptical-shaped figure, substantially as above described and shown.
5. The design for stove, consisting of the dome A, paneled section B, paneled section C, plate D, ash-pit walls E, doors F, the base and rest G, substantially as above described and shown.

WM. L. McDOWELL.
